UNITED STATES PATENT OFFICE.

GEORG HAGELLOCH, OF ESSEN, GERMANY, ASSIGNOR TO FRIED. KRUPP AKTIEN-
GESELLSCHAFT, OF ESSEN-ON-THE-RUHR, GERMANY.

ENDLESS-TRACK ARRANGEMENT FOR VEHICLES.

1,386,926.

Specification of Letters Patent. Patented Aug. 9, 1921.

Application filed September 3, 1920. Serial No. 408,097.

To all whom it may concern:

Be it known that I, GEORG HAGELLOCH, residing at Essen, Germany, a citizen of the German Republic, have invented a certain 5 new and useful Improvement in Endless-Track Arrangements for Vehicles, for which my legal representative, Fried. Krupp Aktiengesellschaft, has filed an application in Germany on December 9, 1918, of which the 10 following is a specification.

This invention relates to that class of endless track arrangements for vehicles, in which guide rollers are provided for that particular part of the endless track, which 15 is in contact with the ground, such guide rollers being so arranged that each roller is movable against the action of a spring, which presses them against the endless track.

The invention consists first and foremost 20 in the fact that not only the guide rollers are elastically supported relatively to their carriers but that these latter are also elastically supported relatively to the frame of the vehicle.

25 The invention will be further described with reference to the accompanying drawings, which show the invention as applied to an armored motor driven car.

Figure 1 is a side elevation of the motor 30 car.

Fig. 2 shows a portion of Fig. 1 on a larger scale, principally in section,

Fig. 3 is a section on the line 3—3 of Fig. 1 looking from the right and

35 Fig. 4 is a section on the line 4—4 of Fig. 2.

The frame of the vehicle has two longitudinal bearers each consisting essentially of two cheeks A (see particularly Figs. 3 and 4), in each of which two longitudinal bearers are mounted the shaft B of a driving wheel B¹ (see Fig. 1) and the shafts C of 40 guide rollers C¹ for an endless track D. Other rollers E, which guide that particular 45 part of the endless track, which is in contact with the ground, are pivotally mounted on a carrier F (see particularly Fig. 3), of substantially channel shape in transverse section and mounted between the 50 two cheeks A. Between the carrier F, which is connected by a connecting rod L to the cheeks A and the cheeks A themselves are interposed supporting springs G (see Figs. 1 and 3), which springs G are rigidly at-

tached to the carrier F by bolts g¹ and connected by connecting rods g² to bolts A¹ carried in the cheeks A. The guide rollers E are pivotally mounted in pairs on bolts K carried in the carrier F, and by means of bell crank levers H, J in which the spindles e¹ of the pairs of rollers are carried. The bell crank levers H embrace by means of eyes h¹ (see Figs. 3 and 4) the bolts K on both sides of a common hub i¹ (see Figs. 2, 3 and 4) of the bell crank levers J. 55

Between the free limbs of the bell crank levers H, J attached to each pair of rollers E, is interposed a previously stressed spherical spring M, which bears with one end against an abutment N (see Figs. 2 and 3), 60 which is pivotally mounted on a bolt h² mounted on the bell crank levers H, and with its other end against a shoulder p¹ (see Fig. 2) of a bolt P, which is pivoted to a bolt i² mounted on the bell crank levers J. 70 Stops h³, i³ (see Figs. 2 and 4) are provided for limiting the swinging movement, which the bell crank levers are capable of executing with respect to each other under the action of the springs M. The opposite 75 movement of the levers H, J, which therefore takes place against the action of the springs M, is limited, by the front portion p² (see Fig. 2) of the bolt P striking against the abutment N. Stops f¹ (see Figs. 1, 2 and 80 3) are also provided on the carrier F for the bell crank levers H, J. 85

The tension of the springs M is so calculated with respect to the weight of the vehicle, that in the case of a constant load the 90 parts of the arrangement described assume the position shown in the drawing. When the vehicle is on the move and jolting occurs, the shocks are first absorbed by the springs M, and in the case of particularly 95 violent shocks the springs G interposed between the frame of the vehicle and the carrier F for the rollers also come into operation. The passage of the vehicle over obstacles such as stems or trunks of trees, 100 stones, ditches and the like is greatly facilitated by the fact, that each pair of rollers (E) can swing about the axis of the corresponding bolt in one direction or the other, the endless track D being provided for this purpose with such an amount of slack that it is able to adapt itself to the inequalities 105 of the ground over which it passes. As the

rollers E are permanently pressed by the springs M against the endless track, the track is prevented from slipping off the guide rollers, and in this way as uniform as possible a strain caused by loading is also insured of the several parts of the track.

Claims:

1. In an endless track vehicle, having guide rollers engaging that part of the endless track which is in contact with the ground, a carrier for said rollers, levers pivoted in pairs to said carrier and carrying
- 10

said rollers in pairs, and springs interposed between the levers of each pair.

2. A construction set forth in claim 1, 15 having springs interposed between said carrier and the vehicle frame.

The foregoing specification signed at Essen, Germany, this 2nd day of June, 1920.

GEORG HAGELLOCH.

In presence of—

HANS GOTSMANN,
JOSEF OLBERTZ.
